UNITED STATES PATENT OFFICE.

GUSTAVUS H. MARQUARDT, OF CASSVILLE, MISSOURI, ASSIGNOR OF ONE-HALF TO THOMAS J. TALBERT, OF CASSVILLE, MISSOURI.

GASOLENE-ENGINE.

No. 922,009.

Specification of Letters Patent. Patented May 18, 1909.

Application filed August 27, 1908. Serial No. 450,415.

To all whom it may concern:

Be it known that I, GUSTAVUS H. MARQUARDT, a citizen of the United States, residing at Cassville, in the county of Barry and 5 State of Missouri, have invented certain new and useful Improvements in Gasolene-Engines, of which the following is a specification.

My invention has relation to new and useful improvements in gasolene engines, and it is so designed that the same action occurs in each end of the cylinder; thus there will be an impulse for every stroke, two impulses for every revolution, except when the engine is 15 over speeding, the fuel supply being cut off by a governor designed for that purpose.

It will readily be deduced from the above that the engine consists of but one piston and one cylinder.

20 The main object of my invention is to produce an engine of the type referred to that will operate on the same principles as that of a steam engine, its smoothness of operation being due to the fact that the manner in which the cylinder is designed gives the piston a "double action" which keeps up a steady uninterrupted movement of the fly wheel of the engine. It is obvious that an engine of this type should have a number of 25 advantages over one having a "single action" cylinder, some of which are in the nature of simplicity of construction, as a lesser amount of machinery is required to develop the same amount of power, other advantages being economy, smoothness of operation, etc.

It is observed that an engine of my construction should be adapted for all classes of work.

Although gasolene is preferably used as a 40 fuel in the operation of my engine, other fuels, adapted for the purpose, such as crude oil or alcohol, or their equivalents, may be employed.

Another advantage my device has over 45 others is that it may be used either as a vertical or horizontal engine.

With these and other objects in view, my invention consists of the novel construction and arrangement of parts as are hereinafter 50 described in the following specification, illustrated in the accompanying drawings forming a part thereof, and particularly pointed out in the claims hereunto appended.

References being had to the drawings, Figure 1 is a side elevation of my device disclosing in general the several features of my invention. Fig. 2 is a top plan view of the same. Fig. 3 is a longitudinal sectional view of my engine, showing the relation of the cylinder and piston to one another. Fig. 4 is a 60 side elevation of the piston. Fig. 5 is a top plan view of the same, partly broken away. Fig. 6 is a cross sectional view of the piston taken on the line 6—6 of Fig 4. Fig. 7 is a vertical sectional view of the cylinder and 65 piston taken on the line 7—7 of Fig. 3. Fig. 8 is a sectional view taken through the governor, disclosing the manner in which the flow of the fuel used is regulated. Fig. 9 is a vertical sectional view of a pump, preferably 70 employed in the operation of my engine, to supply gasolene to the mixer.

Referring more particularly to the drawings my invention is described as follows:

The cylinder 1, formed in two sections 2 75 and 3, is provided with flanges 4, one on the inner end of each of said sections, said flanges being provided for the purpose of securely bolting said sections together. The cylinder is closed at each of its ends by means of removable screw heads 5. Each of said sections is so formed that compartments 6 and 7 are left at the outer end portions thereof for the reception of water or other liquid, said liquid being for the purpose of preventing the 80 temperature of said cylinder from rising to too great a degree. Cut in the upper portion of the outer shells of these compartments are openings 8 and 9, affording means of communication between said compartments and adjacent tanks 10 and 11, mounted securely on the upper surface of said cylinder, one near each of its ends, each of said tanks being provided with a drain cock 12.

The piston 13, is provided at each of its 95 ends with removable deflectors 14, securely held thereto by means of rivets or other substantial means. The design of the piston is such as to provide an air chamber for supplying each end of the cylinder with air. The 100 two extreme positions which may be assumed by either end of said piston are illustrated in Fig. 3, the different vents and ducts being so arranged as to allow the vaporized gasolene and air to pass from the mixer into one of the 105 air chambers in the piston, while in one posi-

tion, and at the same time pass from the other air chamber in the piston into its section of the cylinder. When the piston assumes its other extreme position the same action takes place as described, except in reverse ends of said cylinder. So that each end of the cylinder operates without connection whatsoever with the opposite end, partitions 15 and 16, are supplied to said cylinder, their 10 inner edges coming into contact with the flattened recessed portions 17 and 18, respectively, of said piston. (See Figs. 4 and 5). Cut in the inner edge of each of said strips is a longitudinal recess 19; and into these recesses are inserted strips 20, held outwardly by means of coil springs 21, against the flattened surface of said piston. Said strips are made of any material adapted to prevent the passage of gases from one end of said 15 cylinder into the other. Cut in each side of said cylinder is a longitudinal slot 22, through each of which protrudes one of the ends of the wrist pin 23. Said wrist pin passes through said piston and is firmly held thereto. 20 Power is transmitted from the crank shaft 24, to said wrist pin by means of two connecting rods 25 and 26, which are connected at their forward ends to said wrist pin and at their rear ones to said crank, either directly, or by 25 some medium, as a disk 27. A fly wheel 28, pulley 29, on which travels the band leading to the governor, and drive pulley 27, are all carried by said crank shaft.

The air and fuel reach the closed ends of 30 the cylinder, alternately, through the inlet channels 31 and 32, which are nearly directly over the conjunction of the cylinder sections. Valve stems 33 and 34, which are preferably of the spring actuated type, are 35 adapted to prevent the escape of air or gas from said cylinder. The burned gases escape through the exhaust pipes 35 and 36, when the piston assumes one of its extreme 40 positions. It is obvious that the gases, after the explosion and expansion thereof, will cause pressure to be exerted upon one end of the piston during its time of travel from one extreme position to the other, or until one of the exhausts is automatically 45 exposed, affording an exit for said burned gases. The air is drawn in through the suction pipe and mixed with the gasoline, which is pumped into the feeder by means of the pumps 37, operated by means of the belt 38, 50 traveling on the pulley 39. The mixer 40 is located over said valves 31 and 32, the function of which has been described. Said feeder 41, communicates with the mixer 40, through a small hole, into which a nozzle 42 55 is screwed, said nozzle extending into said mixer approximately one half its width, for the purpose of coming into contact with the tip 43, of the rod 44, which approaches and re-edges from the outer end of said nozzle

according to the velocity of the rotation of the governor 45. The faster the travel of said governor, the nearer said tip of said rod approaches the mouth of said nozzle, until finally, when the velocity becomes too great, the mouth of said nozzle is temporarily closed until the speed falls back once more to the normal. It is observed that the speed of the governor is in turn regulated by the revolutions of the crank shaft, as said band 38, is operated by a pulley 29, keyed to said shaft, said governor being connected to the same shaft whereto the other pulley 46, whereon said band travels, is keyed. The construction of said governor is so common that a description of the same is thought unnecessary. The flow of fuel from the feeder 41, into the mixer, may be regulated at any time by the needle valve 47, the construction of which is common.

Referring again to the piston, it is pointed out that strips 48 and 49, similar to those indicated by the numeral 20, are inserted in longitudinal recesses cut in either side of said piston. The function of said strips is to prevent the escape of gases through the longitudinal slots 22, cut in either side of the cylinder. (See Fig. 7). Annular rings 50, known as piston rings, which are made of suitable material adapted for the purpose, are inserted in annular recesses cut in each 95 end of said piston. These piston rings afford a snug fit of the piston in the cylinder, thus preventing the escape of useful gases.

The manner of igniting the gases in my device is common, and therefore is indicated 100 diagrammatically at 51 and 52. The cam 53 is tripped by means of an extension arm 54, connected to the connecting rod 25. The cam 55 is tripped by means of a projection 56, secured to said arm 25.

Although I have specifically described my invention I may claim the right to make such modifications and changes in the details of construction and arrangement of parts as do not affect any of the rights set 110 forth in the claims hereunto appended.

Having described my invention, what I claim as new and desire to secure by Letters Patent, is:—

1. In a gasoline engine a cylinder composed of two sections, each of which is provided with a flange on its inner end, said flanges registering with one another, adapting said sections to be secured together, said cylinder provided with compartments near 115 the outer ends thereof, said compartments being closed by means of removable screw heads, tanks mounted on said cylinder near each of its ends, openings in said cylinder affording means of communication between 120 said compartments and said tanks, a mixer mounted on said cylinder at its center, valve 125 regulated channels running from said mixer

to said cylinder, a feeder communicating with said mixer secured thereto, a governor to regulate the flow of fuel from said feeder to said mixer, said cylinder further provided with longitudinal slots cut in each side thereof, a piston having a wrist pin extending therethrough at right angles to the longitudinal axis thereof, said wrist pin working in said slots in said cylinder, said piston adapted to fit snugly in said cylinder at each end, so as to respond to explosions occurring at either end of said cylinder, means to conduct fuel to either end of said cylinder and means to explode the same, and means for the exit 15 of burned gases after each explosion, partitions provided in the cylinder dividing the same into two uncommunicating sections.

2. In a gasoline engine a cylinder having partitions dividing it into two uncommunicating sections, a piston, the ends of which are similar, each of which fits snugly into one of the sections of said cylinder, the central portion of said piston being recessed and flattened, said partitions of said cylinder coming 25 into contact with said flattened portions of said piston, said partitions provided with longitudinal recesses, strips of suitable material inserted into said recesses and held outwardly, by means of springs, against the 30 flattened surfaces of said piston, said strips coöperating with said partitions to prevent the passage of gases from one section to the other, means to furnish fuel to said cylinder, means for the exhaust of burned gases, 35 means to automatically regulate the flow of fuel into said cylinder, said cylinder provided with longitudinal slots, said wrist pin of said piston working backward and forward in said slots, communicating its reciprocating 40 motion to a crank shaft by suitable means.

3. In a gasoline engine, a governor automatically operated by means of a belt traveling on a pulley keyed to the crank shaft thereof, said governor provided with a tipped 45 rod, a mixer, a feeder, said feeder formed to said mixer and communicating therewith by means of an internally-threaded small hole, a nozzle screwed into said hole, said nozzle extending into said mixer approximately one 50 half its width and adapted to come into contact with the tip of said rod, said rod adapted to approach and recede from said nozzle according to the velocity of the rotation of said governor, said tip for the purpose of cutting 55 off the source of fuel supply when said engine is overspeeding.

4. In a gasoline engine of the kind described comprising one cylinder and one piston working in said cylinder, strips, a plurality of annular-shaped ones inserted in annular recesses in said piston in each of its ends to cause a snug fit between said piston and said cylinder, said cylinder provided with longitudinal slots in each side thereof near its

center, partitions provided in conjunction with said cylinder on the inner periphery thereof near its center and working in flattened recessed portions of said piston, said piston provided with two longitudinal recesses in each side thereof, strips in said recesses held outwardly against the inner periphery of said cylinder by means of springs to prevent the escape of gases through said longitudinal slots, the inner edges of said partitions provided with strips, inserted in longitudinal slots cut therein, held outwardly against the surface of said flattened portion by means of coil springs, said flattened portions coöperating with said partitions and strips to prevent the passage of gases from 80 one section of said cylinder to the other.

5. In a cylinder of a gasoline engine, partitions secured at the central portions thereof, adapted to work against suitable flattened portions of the piston of said engine, 85 said partitions provided with longitudinal slots, strips in said slots held outwardly against the flattened portions of said piston, by means of springs, said strips and partitions for the purpose of preventing the passage of gases from one section of said cylinder to the other.

6. In a gasoline engine a cylinder composed of two sections held together in a substantial manner, said cylinder provided with compartments at each of its outer ends, said compartments being closed by means of removable screw heads, tanks mounted on said cylinder near each of its ends, slots in said cylinder affording means of communication between said compartments and said tank, a mixer mounted on said cylinder at its center, means of communication between said mixer and said cylinder adapted to be regulated, a feeder communicating with said 105 mixer formed thereon, means to regulate the flow of fuel from said feeder to said mixer, said cylinder further provided with longitudinal slots cut in each side thereof, a piston having a wrist pin extending therethrough 110 at right-angles to the longitudinal axis thereof, said wrist pin passing through said slots in said cylinder, means to conduct fuel to either end of said cylinder and means to explode the same, means provided for the exit 115 of burned gases after each explosion, and means comprising partitions dividing said cylinder into two uncommunicating sections.

7. In a gasoline engine a cylinder composed of two sections held together, means at each end thereof to cool the same after each explosion therein, a mixer mounted on said cylinder at its center, means of communication between said mixer and each of the compartments of said cylinder, said means supplied with spring valves, a feeder formed on said mixer and communicating therewith, means to regulate the flow of fuel into said 125

mixer, said cylinder further provided with slots cut therein, a piston provided with a wrist pin extending therethrough, said wrist pin passing through said slots in said cylinder, means for the conduction and explosion of fuel in said cylinder, means provided for the exit of burned gases after each explosion, said cylinder divided into two uncommuni-

cating compartments, said means comprising partitions substantially as shown. 10

In testimony whereof I affix my signature, in presence of two witnesses.

GUSTAVUS H. MARQUARDT.
